UNITED STATES PATENT OFFICE.

NEWTON L. SNORF, OF CHICAGO, ILLINOIS, ASSIGNOR TO EDMUND & JONES CORPORATION, A CORPORATION OF NEW YORK.

ELECTRIC SWITCH.

Application filed December 2, 1921. Serial No. 519,542.

To all whom it may concern:

Be it known that I, NEWTON L. SNORF, citizen of the United States, residing at Chicago, in the county of Cook and State of Illinois, have invented certain new and useful Improvements in Electric Switches; and I do hereby declare the following to be a full, clear, and exact description of the invention, such as will enable others skilled 10 in the art to which it appertains to make and use the same.

My invention relates to electric switches of the type employing a rocking lever as the operating member, its general objects being 15 those of providing an unusually simple, cheaply manufactured and highly effective construction of such a switch. Furthermore, my invention aims to provide features of construction which might be employed 20 with equal advantages in switches of other types.

In some of its particular aspects, my invention aims to provide a switch in which the contact is made by the forcing of a 25 resilient conducting member against a second contact member which has a rigid portion disposed for resisting the resulting thrust. It also aims to arrange the resilient contact member so that it will automatically 30 hold the pressure-actuating member (which is desirably in the form of a rocking lever) in both its operative and inoperative positions, aims to provide a switch casing having wall portions disposed for cooperating with 35 the yielding contact member in holding the operating member firmly in its "on" and "off" positions, and aims to provide simple means for securing the shaft of the rocking lever to the casing of the switch.

Furthermore, my invention aims to provide as the operating member of such a switch a rocking lever projecting through a portion of the casing of the switch and formed for effectively closing the opening 40 through which it projects when the lever is in either its "on" or "off" position. It also aims to provide simple and effective means for securing the lateral portion of the switch casing to the head or switch front without 45 employing screws or other auxiliary fastening members, and aims to provide simple means for anchoring the cooperating contact members against rotation about the members which fasten them to the insulating 50 base of the switch. Still further and more

detailed objects will appear from the following specification and from the accompanying drawings, in which—

Fig. 1 is a plan view of a switch embodying my invention. 60

Fig. 2 is a side elevation of the same.

Fig. 3 is an enlarged longitudinal section taken along the center line of Fig. 1.

Fig. 4 is a perspective view of the insulating switch base and of the conducting members carried thereby. 65

Fig. 5 is a transverse section taken along the correspondingly numbered line in Fig. 3.

Fig. 6 is a perspective view of the rocking lever or actuating member of the switch. 70

Fig. 7 is a bottom view of the switch.

Fig. 8 is a fragmentary section showing the method of securing the rock shaft to the switch casing. 75

In the embodiment of the drawings, the switch of my invention includes as its casing a cylindrical shell portion 1 equipped at its upper or forward end with a pair of ears 2, which ears extend at right angles to the axis of the shell 1 and bear flatwise against a plate 3. This plate forms the front of the switch and desirably has a rearwardly formed edge portion 4 designed to raise the front from the wall to which it is fastened. Each of the shell ears 2 has a perforation 80 alining with a corresponding perforation in the front plate 3, and the adjacent metal of the front plate 3 is forced through the perforation in the adjoining ear 2 and clinched over the back of this ear as shown in Fig. 3. 85 Thus arranged, the portions of the front plate projecting through these ears form anchoring tubes 5 each of which simultaneously affords an opening through which a screw may be inserted for fastening the front plate to a dashboard or other support and each of which tubes clinchingly anchors the front plate 3 to the shell portion of the casing. 90

The rear of the shell 1 is closed by an 100 insulating head 6 carrying the circuit terminals and the switching or circuit-controlling conductors. Each of the circuit terminals desirably consists of a tubular rivet 7 threaded upon its interior for receiving the shank of a binding screw 8 and extending within the casing through one of the two cooperating contact members. One of these contact members desirably consists of a resilient member 9 formed from a strip of 105 110

bronze or the like and having a perforated base portion 9 bearing against the forward face of the insulating head 6 and clinched against the latter by the forward head of the adjacent tubular rivet 7, and also includes a curved strip portion 10 extending transversely of the shell 1 and somewhat obliquely forward of the latter. When the switch is in its "off" position, this contact strip portion 10 is freely spaced from the tip of a second and substantially inflexible contact member which comprises a riser portion 11 extending towards the contact strip portion 10 and integral with a base portion 12 secured to the insulating head 6 by the other tubular rivet. The riser portion 11 desirably extends approximately at right angles to the adjacent portion of the contact strip 10 and towards a medial portion of the length of the latter, and this contact strip 10 has its free end downwardly curved so as to afford a hump 13 substantially as shown in Fig. 3.

Pivoted to the shell 1 on a shaft 14 extending transversely of the shell 1 near the forward end thereof, and extending substantially at right angles to the common plane of the axes of the two tubular rivets, is a rocking lever which forms the actuating member of the switch and which desirably is made of rubber, fiber or similar insulating material. This rocking lever comprises a handle 15 projecting forwardly beyond the casing through an aperture 16, which aperture is of a sufficient length in a direction parallel to the axis of the shaft 14 to permit the lever to be rocked to a considerable angle about the said shaft, and which aperture approximates the width of the handle 15 sufficiently to prevent a sliding of the lever on the shaft. The lever also includes a rear stem portion 17 having a rounded end which continuously bears against the forward face of the contact strip 10 and which is adapted to slide along this contact strip when the lever is rocked (in a direction which is clockwise in Fig. 3) so as to afford a cam action flexing the contact strip into engagement with the riser portion 11 of the companion circuit terminal. Furthermore, this rounded inner end of the stem 17 is adapted to ride over the said hump 13 when the lever is rocked to afford the contact-insuring flexing of the strip 10, thereby latching the rocking lever yieldingly in the position shown in dotted lines in Fig. 3. To limit the lever in the said direction, I may stop this movement by engagement of the handle 15 against one edge of the aperture 16, namely the right hand edge of Fig. 3. However, this edge might be apt to indent the lever in time, hence I preferably employ either or both of two other means for stopping this movement of the lever. One of these con-

sists in equipping the rocking lever with an arm 18 having a forward face adapted to bear against the rear of the front plate 3 when the rocking lever is in its "off" position. The other consists in proportioning the parts so that the rear end of the rocking lever will engage the bore of the shell 1 when the lever is in its "off" position, or in other words so that this inner end of the lever will be clamped between the shell and the free end of the contact strip 10 after the manner shown in dotted lines in Fig. 3.

To limit the movement of the lever in the other direction, I desirably equip the lever with a second arm 19 extending in the opposite direction from the arm 18 and adapted to engage the rear face of the front plate when the rocking lever is in its "off" position as shown in full lines in Fig. 3.

To prevent the cooperating contact members from rotating about the tubular rivets which secure them to the insulating head 6, I desirably provide each of these contact members with a finger or ear engaging a corresponding recess formation in the head 6, as by providing the contact base 12 with a lug 20 entering a lateral slot 21 in the insulating head, and providing the base 9 of the companion contact member with an ear 22 entering a bore 23 which extends part way through the head 6 from the interior of the latter. Then I anchor the head 6 to the shell 1 against rotation within the latter by any suitable means, as for example by indenting portions 24 of the shell into the periphery of the head 6, the latter being desirably of rubber, fiber or similar material.

With the parts thus assembled, it will be obvious from Fig. 3 that the resiliency of the longer contact member will cooperate with the arm 19 on the rocking lever for holding this lever in its "off" position; that a movement of this rocking lever will first force the contact strip 10 into engagement with the riser portion 11 of the companion contact member and will then snap the inner end of the lever over the hump 13 so as to latch it in its "on" position; also, that by having the riser portion 11 extending transversely of the adjacent part of the contact strip 10 I avoid any tendency towards bending the shorter contact member and enable this riser portion to resist the contact pressure without moving.

Furthermore, it will be evident that the forward face of the arm 19 effectively closes the opening 16 alongside the handle 15 when the lever is in its "off" position and that the companion arm 18 serve the same purpose when the lever is in its "on" position, so that these lever portions act at all times to exclude dust and the like from the switching casing. So also, it will be noted that by clinching the tubular formations 3 of the

front plate through the perforations in the ears 2, I firmly secure this front plate through the shell of the casing without employing any auxiliary fastening elements

5 while also providing a handsome finish for the screw-hole perforations in this front plate.

To facilitate the securing of the shaft 14 to the shell portion of the casing, I desirably reduce the shaft in diameter at each 10 end for a distance corresponding substantially to the thickness of the shell 1, as shown in Fig. 8. Then after slipping the shaft 14 through a corresponding bore in the rocking lever and before securing both 15 the front plate 3 to the shell, I compress the shell slightly in a direction transverse to the shaft, thereby increasing the distance between the two perforations in the shell 1 20 through which the ends of the shaft 14 are to project. Having done this, I can insert the shaft from the adjacent end of the shell into the interior of the latter and snap its ends into the corresponding perforations in 25 that shell. This enables me to effect the mounting of the shaft without added labor or auxiliary fastening elements. In doing so, it is immaterial whether or not the lever is loose on the shaft on the latter, although 30 I preferably drive the lever tightly over the shaft so that the rocking bearing will be between the ends of the shaft and the shell, thereby avoiding wear on the lever.

However, while I have illustrated and described my invention in an embodiment employing various desirable features of construction and arrangement, I do not wish to be limited to these as they might obviously be varied in many ways without departing 35 from the spirit of my invention or from the appended claims. Neither do I wish to be limited to the joint use of all of the various features of this invention, as some of 40 these features might obviously be used in connection with substitutes for other parts. For example, it will be evident that the 45 method of anchoring the switch casing to the front plate as here disclosed need not be limited to switches of the rocking lever 50 type.

I claim as my invention:

1. In an electric switch, a resilient contact member normally yieldingly spaced from a second contact member, a casing 55 housing the said members and including a cover plate provided with an aperture, and a lever pivoted on the casing and projecting through the aperture in the cover and continuously engaging the first named contact member and adapted to force the latter into contact with the second contact member, the first named contact member having a hump over which the engaging portion of 60 the lever rides when moving the contact members into engagement, the casing having a pair of oppositely disposed lateral perforations and the pivotal mounting of 65 the lever including a shaft having ends of reduced diameter respectively socketed in the said perforations, the casing being of resilient material and the shaft being inserted while the casing is distorted to lengthen the 70 distance between the said perforations and 75

a laterally projecting arm disposed for engaging the inner face of the cover of the casing to limit the movement of the lever in one direction.

2. In an electric switch, a resilient contact member normally yieldingly spaced from a second contact member, a casing housing the said members and including a cover plate provided with an aperture, and a lever pivoted on the casing and projecting through the aperture in the cover and continuously engaging the first named contact member and adapted to force the latter into contact with the second contact member, the first named contact member having a hump over which the engaging portion of the lever rides when moving the contact members into engagement, the lever having a pair of oppositely directed arms disposed for engaging the inner face of the cover of the casing to limit the movement of the lever respectively in both directions.

3. In an electric switch, a resilient contact member normally yieldingly spaced from a second contact member, a casing housing the said members and including a cover plate provided with an aperture, and a lever pivoted on the casing and projecting through the aperture in the cover and continuously engaging the first named contact member and adapted to force the latter into contact with the second contact member, the first named contact member having a hump over which the engaging portion of the lever rides when moving the contact members into engagement, the axis of the lever being pivoted at one side of the said aperture in the cover and the lever having a lateral projection disposed for engaging the inner face of the cover to limit the movement of the lever in one direction and to close the portion of the aperture at that side of the lever.

4. In an electric switch, a resilient contact member normally yieldingly spaced from a second contact member, a casing housing the said members and including a cover plate provided with an aperture, and a lever pivoted on the casing and projecting through the aperture in the cover and continuously engaging the first named contact member and adapted to force the latter into contact with the second contact member, the first named contact member having a hump over which the engaging portion of the lever rides when moving the contact members into engagement, the casing having a pair of oppositely disposed lateral perforations and the pivotal mounting of the lever including a shaft having ends of reduced diameter respectively socketed in the said perforations, the casing being of resilient material and the shaft being inserted while the casing is distorted to lengthen the distance between the said perforations and 125

being normally held in place by the resiliency of the casing.

5. In an electric switch, a resilient contact member normally yieldingly spaced from a second contact member, a casing housing the said members and including a cover plate provided with an aperture, and a lever pivoted on the casing and projecting through the aperture in the cover and continuously engaging the first named contact member and adapted to force the latter into contact with the second contact member, the first named contact member having a hump over which the engaging portion of the lever rides when moving the contact members into engagement; the end of the lever which engages the first named contact member being adapted to engage the bore of the casing after riding over the said hump so as to limit the movement of the lever past the hump.

6. In an electric switch, an insulating base, a substantially inflexible contact mem-

ber secured thereto and including a riser arm extending obliquely forward from the base, a second contact member secured to the base and having a free ended resilient portion extending past the tip of the said riser arm and approximately at right angles to the latter, and a lever movable into and out of a position in which it engages the said resilient portion between its free end and the part adjacent to the tip of the riser arm to flex the said resilient portion into contact intermediate of its length with the tip of the riser arm.

7. An electric switch as per claim 6, in which the lever when in its said contact flexing disposition engages the bore of the casing and in which the free end of the resilient contact member portion is arranged for latching the flexing means in its last named position.

Signed at Chicago, Illinois, November 26th, 1921.

NEWTON L. SNORF.
